UNITED STATES PATENT OFFICE.

SWAN N. TEVANDER, OF MAYWOOD, ILLINOIS, ASSIGNOR TO AMERICAN CAN COMPANY, OF NEW YORK, N. Y., A CORPORATION OF NEW JERSEY.

CONTAINER-CLOSURE.

1,348,601.

Specification of Letters Patent. Patented Aug. 3, 1920.

Application filed February 18, 1916. Serial No. 79,040.

To all whom it may concern:

Be it known that I, SWAN N. TEVANDER, a citizen of the United States, residing in Maywood, in the county of Cook and State 5 of Illinois, have invented a new and useful Improvement in Container - Closures, of which the following is a specification.

This invention relates in general to containers and has more particular reference 10 to closures for the same. In the present instance it is shown as applied to a can nozzle, although it will be manifest, as the invention is better understood, that it can be embodied in other forms of closure.

15 A principal object of this invention is the provision of a can or container closure which will be provided with a frangible seal and also with an easily operable and tight holding cover adapted to protect the seal in the marketing of the package, and also to form a closure for the can or container after the seal has been broken by the consumer.

20 Other objects and advantages of the invention will be apparent as it is better understood from the following description when considered in connection with the accompanying drawing illustrating a preferred embodiment thereof.

25 Referring to the drawing,

Figure 1 is a side elevation of a can or container closure embodying my present invention taken through the body of the can and at one side of the closure;

30 Fig. 2 is a vertical section through the can and parts of the closure affixed thereto;

Fig. 3 is an enlarged similar view showing the completed closure;

35 Fig. 4 is a section through the cover or cap; and

Fig. 5 is a section through the blank used in the present embodiment to form the can closure.

The nozzle proper, designated at A, is 40 positioned on the top of a can body proper B, to which it is secured by a seam C. The nozzle A is of cylindrical form and is provided near its upper or open end with an inwardly extending depression or bead 7 45 which is flattened to constitute an internal annular flange disposed just beneath its upper open end. Upon this flange is seated a frangible closure 8 consisting of a disk of paper, cardboard or the like which may be

treated with paraffin or other proofing substance if desired. The upper edge 9 is curled down upon the disk 8 to hold it in place and prevent its removal bodily from the container, making it necessary to cut through the disk to get at the contents. 55

A slip cover D is provided, and this slip cover is depressed at its center 10 to press down upon the disk 8 and reinforce it when the container is inverted, thus permitting a thin and frangible disk to be used if desired. About the depression 10 extends a raised annular part 11 in which is disposed the curled edge 9. The annular flange 12, which embraces the outside of the nozzle or can top, extends downwardly from the 60 outer edge of the part 11 and is provided with an encircling outwardly extending bead 13. A number of slits 14, extending vertically upwardly to and through the bead 13, render the flange 12 elastic or yielding so 65 that it may be made slightly smaller than the external diameter of the outer face of the nozzle or can top. This flange is of such length that its lower edge 15 is disposed at and slightly in the depression 16 70 formed by providing the bead 7. In this depression the edge 15 engages by reason of the yielding nature of the parts of the flange set off by the slits 14.

This cover may be merely pulled from 75 place when access to the interior of the container is desired, removal of the cover permitting easy fracturing of the seal or disk 8 and the cover is adapted for subsequent use as the sole closure. 80

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof. 85

I claim:

1. A container having a nozzle provided with an inwardly extending flattened head, a frangible seal seated on said head, the upper edge of said nozzle being curled down thereupon to secure it in place, and a slip cover having a depressed central portion bearing on said seal and having a flange en-

gaging the exterior of the nozzle frictionally and removably.

2. A container having an open top, and formed with an inwardly extending bead 5 near the opening of the top; a seal disk resting on said bead; and a slip cover having a depressed central portion 10, a raised annular part 11 embracing the edge of said opening, and a flange which engages frictionally and removably the exterior of the container around said opening.

3. A container having an open top, and bent inwardly near the opening of said top to form an exterior depression 16 and an inwardly extending bead 7; a seal disk supported on said bead; and a slip cover having a slotted spring flange engaging in said exterior depression.

4. A container having an open top, and 20 bent inwardly near the opening of said top to form an exterior depression 16 and an inwardly extending bead 7; a seal disk supported on said bead; and a slip cover engaging on top of said disk and having a slotted spring flange engaging in said exterior depression.

5. A container having an open top, and an inwardly extending bead beneath said 30 open top, a seal resting upon said bead, a cover having a central portion engaging said seal, and a spring depending flange embrac-

ing said top and engaging at its lower edge in the depression formed without said bead.

6. A container having an inwardly bent shoulder, a frangible seal resting thereon, 35 the edge of the container being curled inwardly down on said seal to permanently clamp it to said shoulder, and an outer removable and replaceable cover having a central depressed portion bearing on said seal, a 40 raised rim portion passing over around the curled edge of the container and a depending flange engaging around the exterior of the nozzle.

7. A container nozzle having an inwardly 45 bent shoulder of double thickness forming an exterior depression, a frangible seal resting on said shoulder, the edge of the container being inwardly bent and clamping the seal permanently in place, and a removable 50 slip cover inclosing said nozzle and formed with a resilient depending flange having means engaging removably in said exterior depression.

In testimony whereof I have hereunto set 55 my hand in the presence of two subscribing witnesses.

SWAN N. TEVANDER
